UNITED STATES PATENT OFFICE.

JOHN WALLACE JAKEMAN, OF ALTRINCHAM, ENGLAND, ASSIGNEE TO LINOTYPE AND MACHINERY LIMITED, OF LONDON, ENGLAND.

SHEET-DELIVERY MECHANISM FOR PRINTING MACHINES.

Application filed May 6, 1926, Serial No. 107,024, and in Great Britain May 15, 1925.

In a well-known type of sheet delivery mechanism applicable to printing machines in which the sheet travels in only one direction from the cylinder to the delivery board, the printed sheet is delivered from the impression cylinder on to endless tapes moving linearly at or about the circumferential speed of that cylinder, and is thence transferred to other endless so-called carriage tapes carried upon a reciprocating carriage.

During one stroke of the carriage, the carriage tapes remain stationary with respect to the carriage and on the other stroke they are caused to revolve relatively to the carriage at such speed that the upper flights upon which the sheet rests, remain stationary in space.

In some machines, as for example a single revolution machine with the delivery at the feed-board end, it is necessary to reverse the direction of travel of the sheet by means for example, of a take-off or delivery cylinder, in order that said sheet may be delivered with the printed side upwards.

Hitherto when a tape carriage delivery has been fitted to such a machine, it has been usual either to provide separate tapes, not attached to the carriage, to carry the sheet back from the take-off cylinder or, where a single set of tapes is used, to attach one end of the tapes to the carriage or to a roller mounted on the carriage and the other end to a roller mounted in the frame of the machine.

Both these arrangements have the disadvantage that some part of the tapes is underneath the cylinders of the machine and therefore in a position very difficult of access.

The present invention has for its object to overcome the aforesaid difficulties and to that end it consists in a new or improved construction wherein the whole of the tapes are mounted on, and carried to and fro by, the carriage, so that they are completely and very conveniently accessible for renewal or repair.

The tape carriage which is reciprocated

by any convenient means, carries, at each end, a transverse shaft which is encircled by endless tapes.

Other tapes, herein called the top tapes, are attached at each end to bars extending transversely across the two ends of the carriage.

Each of these top tapes passes over an upper roller and under a lower roller rotatable about their respective stationary axes, the rollers being so disposed that these top tapes are above the upper flights of the endless tapes at the rear end of the carriage and below them at the front end.

The invention will now be described by reference to the accompanying drawings in which:—

Figure 1 is a diagrammatic side elevation of the pertinent parts of a lithographic rotary printing machine embodying one constructional form of the said invention;

Figures 2 and 3 are views similar to Figure 1 but drawn to a smaller scale and showing the improved delivery mechanism in respectively different positions;

Figure 4 is an isometric perspective view of part of the delivery mechanism and with the different parts represented, shown in the same positions as those respectively occupied by them in Figure 1, and

Figure 5 is a view showing means for operating the carriage tapes.

Throughout these figures like reference numerals are used to indicate corresponding parts, and arrows are employed to indicate directions of motion.

In Figure 1, as in Figures 2 and 3, 1 is the impression cylinder, 2 the plate cylinder, and 3 the take-off or delivery cylinder, all of which may be of ordinary construction and operated in usual manner.

4 is the tape carriage which is of the usual rigid rectangular construction embodying two side members which are themselves identified by the reference numerals 4, and are rigidly connected together at their rear ends by a bar 4^a and near their front ends by a bar 4^b, the whole being supported on track rollers 5 adapted to run along track

rails 6 carried by delivery way brackets 7 which are secured to the frame or base 8 of the machine.

For convenience of description the end of the tape carriage 4 which is at the left-hand side of each of the figures, is herein termed the rear end as distinguished from the opposite or right-hand end shown in those figures which latter end is herein termed the front end; similarly the travel of the carriage leftward and rightward of the several figures is hereinafter referred to as the in-stroke and out-stroke respectively.

The tape carriage 4 is reciprocated along the rails 6 by any convenient means; those shown for the purpose in Figures 1, 2 and 3, consist of a crank 9 fast to the impression cylinder shaft 10, a rod 11 connecting said crank to a lever arm 12 fast on a rock shaft 13 on or near either end of which is secured a bent arm 14 pivotally connected to one end of a link 15 whose opposite end is pivoted to the front end of the respective side carriage-member 4.

25 At the front and rear ends of the tape carriage 4 there are pivotally mounted shafts 16 and 17 respectively, the former having tape pulleys 18 fast thereon, which are encircled by the endless tapes 19 which also encircle and in the example illustrated run directly upon the shaft 17.

20 indicates the before mentioned top tapes of which the rear and front ends are attached to the bars 4^a and 4^b respectively and each of which passes over an upper roller 21 and under a lower roller 22. These rollers 21, 22 rotate about stationary axes, being pivotally supported on standards 23 rigidly secured to a cross bar 24 which itself is rigidly connected to the before described delivery way brackets 7.

The rollers 21, 22 are so located that the top tapes 20 are above the upper flights of the endless tapes 19 at the rear end of the tape carriage 4 and below them at the front end of the latter.

25 and 26 represent the feed board and delivery board respectively, 27, 28 the sheet grippers of the impression cylinder 1 and delivery cylinder 3 respectively, and 29 pulleys or rollers between which and the last named cylinder the sheets are carried round, the said pulleys being so disposed as to engage only the margins of such sheets.

55 The tape carriage 4 is preferably provided with a series of catch fingers 30 adjustable along bars 31 extending longitudinally of the said carriage and supported by brackets 32 attached to the transverse bars 4^a, 4^b; these catch fingers when provided, serving for limiting the movement of the sheets X towards the back of the tape carriage; it is, however, to be noted that the fingers 30 may be dispensed with, as they are not in-

dispensable to an efficient working of the delivery mechanism.

The intermittent rotation imparted to the tape pulley shafts 16, 17, is derived from means such as those already known in the art; for instance, as shown in Figure 5, the operation of the carriage tapes may be controlled by a sprocket chain 33 which engages with a sprocket wheel 34 fast on the shaft 16, and with which is adapted to engage a chain stop 35 during the instroke of the tape carriage 4. The chain stop is fast on a rockshaft 36 journalled in the machine frame and on this shaft is also secured a toggle arm 37 which co-operates with a second toggle arm 38 to retain, under the influence of a spring 39, the chain stop 35 in its terminal positions, until it is positively moved therefrom, these said positions being determined by two adjustable stops 40. On the rockshaft 36 are also secured roller-carrying arms 41, 42 with which, at respectively opposite ends of the travel of the carriage 4, engage tumblers 43, 44 respectively. These tumblers are pivotally mounted on said carriage so that at the commencement of the inward stroke of the tape carriage 4 (which is the phase represented in Figure 5), the tumbler 43 engages the arm 41 and on the continued movement of the carriage, lowers the chain stop 35 into engagement with the chain 33; and at the commencement of the outward stroke the chain stop is raised out of engagement with the said chain, by a corresponding action of the tumbler 44 on the arm 42 whereby, during the continued outward travel of the carriage, the upper flight of the sprocket chain 33 is carried along by and as if in one piece with, the carriage.

When the tumbler 43 or 44 contacts with the arm 41 or 42 just prior to the carriage reaching the respective end of its travel, the said tumbler is depressed against the action of a spring 45 which immediately thereafter returns it to its normal position against a stop 46.

The operation of the before described arrangement will now be described with particular reference to Figures 1, 2 and 3, wherein sheets X, represented by chain-dotted lines, are shown at respectively different stages of delivery and in which the carriage is represented, in Figure 1 at the extreme end of the in-stroke, in Figure 2 at the extreme end of the out-stroke, and in Figure 3 at midway, or about midway, of its in-stroke.

In said operation a sheet X taken from the feed-board 25, by the impression cylinder grippers 27, is carried between the plate cylinder 2 and the impression cylinder 1 until it is seized by the grippers 28 of the delivery cylinder 3, the printed sheet there-

after being carried round between the delivery cylinder and pulleys 29 which engage the margins of said sheet. When the delivery cylinder grippers 28 are in or about in their lowest position, as shown in Figure 2, the leading edge of the sheet X, is released by them and falls upon the top tapes 20 which, with the tape carriage 4, have just commenced their in-stroke.

10. As this stroke of the tape carriage 4 proceeds, the sheet X is laid upon the top tapes 20, as shown in Figure 3, the margin pulleys 29, assisting in driving said sheet in the direction of the carriage travel until, just 15 before the end of the in-stroke, the tail end of the sheet leaves the margin pulleys 29 and falls upon the endless tapes 19.

The tape carriage 4 then commences its out-stroke, during which the sheet X is automatically transferred from the top tapes 20 to the endless tapes 19, which are then at rest in relation to the said carriage.

15. The in-stroke of the tape carriage 4 then commences and during this stroke, the endless tapes 19 are caused to revolve, the linear speed of their upper flights being approximately equal to the linear speed of the carriage but opposite in direction, so that said upper flights are stationary or almost stationary relatively to the frame of the machine.

During this stroke, a second sheet X may be deposited on the top tapes 20 from the delivery cylinder 3, while, owing to the rotation of the endless tapes 19, the previous sheet X is being deposited on the delivery board 26, all as shown in Figure 3.

Having described my invention, I declare that what I claim and desire to secure by 40 Letters Patent is:—

1. Sheet delivery mechanism for printing machines, comprising a reciprocating tape carriage, two sets of tapes both reciprocating with the carriage, one set serving for receiving the printed sheets and transferring them to the other set, the tapes of the latter set being endless and serving to deposit the sheets on the delivery board, and means for rotating the endless tapes during only 50 the inward strokes of the carriage.

2. Sheet delivery mechanism according to claim 1, comprising means at relatively different ends of the carriage attaching to said carriage the two ends of each tape of one set at relatively different levels, and a stationary support over which said tape passes at a part intermediate its ends to support it at the higher level.

3. Sheet delivery mechanism for printing machines comprising a reciprocating tape carriage, two sets of tapes both reciprocating with the carriage, one set serving for receiving the printed sheets and transferring them to the second set which in turn deposits them on the delivery board, and in which

each tape of one set is attached to the tape carriage by its two ends at relatively different levels, and at relatively different ends of the carriage and at a part intermediate its ends passes about pulleys rotating about stationary axes and supporting said tape at its different levels.

4. Sheet delivery mechanism for printing machines comprising a reciprocating tape carriage, two sets of tapes both reciprocating with the carriage, one set serving for receiving the printed sheets and transferring them to the second set which in turn deposits them on the delivery board, and in which each tape of one set is attached to the tape carriage by its two ends at relatively different levels, and at relatively different ends of the carriage characterized by the tapes of the second set being endless and adapted to be rotated during only the inward stroke of the carriage.

5. In sheet delivery mechanism for printing machines, the combination with a reciprocating tape carriage, of two sets of tapes both reciprocating with the carriage, the tapes of one set being endless and having their upper flights located in a given plane while those of the other set are at their ends fixedly attached to the tape carriage at levels respectively above and below the said plane.

6. In sheet delivery mechanism for printing machines, the combination with a reciprocating tape carriage, two shafts rotatable in relatively opposite ends of the carriage, endless tapes encircling said shafts and rotating during only the inward stroke of the tape carriage, bars fast to respectively opposite ends of the carriage, tapes fixedly attached by their ends to the bars, and rollers rotatable about stationary axes and guiding said tapes at parts intermediate their ends at different levels respectively above and below the plane containing the upper flights of the endless tapes.

7. In sheet delivery mechanism for printing machines, the combination with a reciprocating tape carriage, two shafts rotatable in relatively opposite ends of the carriage, endless tapes encircling said shafts and rotating during only the inward stroke of the tape carriage, bars fast to respectively opposite ends of the carriage, tapes fixedly attached by their ends to the bars, rollers rotatable about stationary axes and guiding said tapes at parts intermediate their ends at different levels respectively above and below the plane containing the upper flights of the endless tapes, and catch fingers adjustable on the carriage for limiting the movement of the sheets on said carriage.

8. In sheet delivery mechanism for printing machines, the combination of a tape carriage, track rails along which the tape carriage is free to travel in different directions, mechanism adapted to reciprocate said car-

riage along the track rails, two shafts rotatable in relatively opposite ends of the carriage, tape pulleys fast on one of these shafts, endless tapes encircling these rollers and the other of said shafts and rotating during only the inward stroke of the tape carriage, tapes fixedly attached by their ends to relatively opposite ends of the tape car-

riage, and rollers guiding said tapes at parts intermediate their ends at different levels ¹⁰ one above and the other below the plane occupied by the upper flights of the endless tapes.

In testimony whereof I have affixed my signature hereto.

JOHN WALLACE JAKEMAN.
